LOUIS H. THULLEN, OF EAST ORANGE, NEW JERSEY

GRINDING OR CUTTING APPARATUS

Application filed November 29, 1926. Serial No. 151,306.

My invention relates to improvements in cutting apparatus and more particularly to apparatus for cutting or grinding wood or the like for the purpose of making comminuted wood or similar materials. The main object of the invention is to provide an apparatus which operates more evenly and efficiently and without danger to the parts. Further and more specific objects, features 10 and advantages will more clearly appear from the detailed description given below taken in connection with the accompanying drawings which form a part of this specification.

15 In the drawings, Fig. 1 is a view largely diagrammatical illustrating apparatus embodying my invention in a preferred form thereof;

Fig. 2 illustrates a modified form of the 20 arrangement for feeding the wood or the like to the grinding element;

Fig. 3 is a section taken substantially on the line 3—3 of Fig. 1;

Fig. 4 is a vertical section illustrating a 25 modified arrangement for applying the material to be ground to the grinding element; and

Fig. 5 is a vertical section illustrating a 30 still further modification.

Referring to Figs. 1 and 3, 6 represents a 35 rotary cutting element or grinding stone rigidly secured on a shaft 7 by suitable clamping plates 8. Shaft 7 rotates in suitable bearings at 9 carried by suitable frame work 10, which also carries a container or passageway 11 into which the wood 12 or other material 40 to be ground is placed. As shown in Figs. 1 and 3, passageway 11 is substantially filled with logs of wood 12. Operating in the pas-

45 sageway 11 is a plunger 13 operated by a spindle 14. The spindle 14 is connected to a piston 15 operating in a cylinder 16. 17 represents a pipe connected to a suitable source of air or other fluid under fixed pressure (preferably oil under pressure) and this pipe is connected to the bottom and top of the cylinder 16 by two passageways 18 and 19 respectively. A manually operated valve 20 may be turned to close the passage 18 and 50 open the passage 19, or close the passage 19

and open the passage 18, so that according to the position of the valve 20 the fluid under pressure from pipe 17 will raise the piston 15 or lower the piston 15 respectively and so raise the plunger 13 or lower the plunger 55 13 and press the wood 12 into engagement with the grinding wheel 6 with a force proportional to the pressure applied to the piston 15.

Rigidly connected to one end of the shaft 60 7 is a casing 21 of a fluid pump. Rotating within the casing 21 is a shaft 22 to the outer end of which is connected a gear 23 by means of which the shaft 22 may be rotated by any suitable prime mover. Within 65 the casing 21 there is provided a frame work 23^a which is non-rotatable with respect to the casing 21 and rotates therewith about the axis of the shaft 22, but may be tilted to various positions within the casing 21 by turning a shaft 24 in a manner not shown, but well understood by those skilled in the art. The frame work 23^a is provided with roller 70 bearings 25 against which there rotates a rotating member 26, pivoted with respect to, 75 but rotated by, the shaft 22, the member 26 being pivoted to the shaft 22 about an axis at 27, which axis extends at right angles to the shaft 22. The shaft 22 has an extension at 28 journaled in the frame 21. Connected 80 to the member 26 by ball and socket joints are piston rods 29 operating pistons 30 in cylinders 31 in the member 32 secured rigidly on the extension 28 of the shaft 22 and rotating therewith.

Assuming the casing 21 be kept stationary and the shaft 22 rotated, the pistons 30 will be caused to move back and forth in the cylinders 31, thereby operating like pumps and the head portion 33 of the casing 21 is 85 provided with certain passages 34 and 35 and grooves at 36 and 37 so that if the passage 34 be connected to a suitable oil or other fluid supply, the same will be drawn into the cylinders 31 when the pistons 30 are moved outwardly therefrom and the oil or other fluid will be compressed in the cylinders 30 and forced out thereof through the passage 35 when the pistons 30 again move back into the cylinders due to the rotation of the shaft 22. 90 95 100

Thus the apparatus acts as a fluid or hydraulic pump and since such pumps are well known in the art further description thereof is believed to be unnecessary.

The shaft 7 is provided with two passages 38 and 39 extending substantially entirely therethrough, which passages communicate with the passages 34 and 35 respectively at the end of the shaft 7 where it is connected to the hydraulic pump frame 21. In the same way passage 39 is connected to the passage 35. At the other end of shaft 7 the passage 38 is connected to a pipe section 40 which extends into a stuffing box 41, which in turn is connected to a tank or other source of oil or fluid supply 42 by a stationary pipe 43. The passage 39 is maintained in open communication with a stationary pipe 44 by means of a suitable stuffing box connection 45. Thus if the shaft 22 be rotated while the shaft 7 be stationary, or if the shaft 22 be rotated at greater speed than the shaft 7 whereby there is relative rotation between the shaft 22 and the fluid pump casing 21, oil or other fluid is withdrawn from the supply tank 42 and is forced out through the passages 35 and 39 into the pipe 44 under pressure.

Pipe 44 leads to a relief or safety valve 46 which, if the pressure in the pipe 44 exceeds a predetermined value, permits the fluid under pressure to escape past the valve into a pipe 47 and back into the supply tank 42. 48 represents another pipe connected to the valve 46 but always in free communication with the pipe 44. The pipe 48 is connected to a reduction valve 49 of any suitable variety and from the valve 49 the fluid under pressure is conducted to the bottom of the cylinder 16 by means of pipe 50. A valve 51 is shown in this pipe so that the pipe may be closed off from the bottom of the cylinder 16 when desired. A branch pipe 52 leads from pipe 50 to a diaphragm motor 53 adapted to actuate a valve 54 in the supply pipe 17, so that with the valve 55 open if the pressure in the pipe 50 reaches a predetermined value it will operate the motor 53 and cause the same to close or partially close the valve 54 and thus shut off or throttle the fluid supplied under pressure through pipe 17 to the top of piston 15 and so relieve the force thus applied tending to press the wood or material to be ground into engagement with the grinding or cutting member. Reducing valve 49 is inserted mainly for the purpose of reducing the pressure applied in the pipes 50 and 52 to a given percent or proportion of that existing in pipe 44, but variations in pressure in pipe 44 will also produce similar percentage variations in pipes 50 and 52.

In operation the shaft 22 is driven by any suitable prime mover through the gear 23 and since the cutting member 6 and shaft 7 tend to remain at rest at first, there will be relative

rotation between the shafts 7 and 22, thereby causing the hydraulic pump to operate and build up a pressure in the passages 35 and 39 and pipes 44, 48 and 50, which pressure is (with valve 55 closed and valve 51 open) opposed by the pressure exerted on the outside of the piston 15. This back pressure tends to cause the fluid pump casing 21 to rotate with the shaft 22 and so rotate the shaft 7 and the cutting or grinding element 6 whereby it operates to cut or grind the wood 12 or other material as desired. If, however, the resistance or load encountered by the cutting or grinding element 6 is too great or increases unduly, then there will be further relative rotation between the shafts 7 and 22 causing a higher pressure to be built up in the passages 35 and 39 and pipes 44, 48 and 50, so that a greater pressure will be exerted on the underneath side of the piston 15 and thereby decrease the force with which the plunger 13 presses the wood or other material into engagement with the grinding member so that the load or resistance which the same offers to the grinding member is decreased, thereby permitting the rotation of the grinding member to return substantially to its normal speed. That is, the pressure or feed with which the material being operated upon is fed relatively to the operating tool is varied in accordance with the resistance or load encountered by the tool in its work on the material operated upon.

The torque exerted by the shaft 7 may be varied and the pressure produced in the passage 34, pipes 44, 48 and 50 may be varied independently of the resistance encountered by the work member 6 by adjusting the shaft 24 so as to change the stroke of the fluid motor and in this way the apparatus may be adjusted for different conditions of work. Any suitable arrangement may be provided for adjusting the shaft 24 for this purpose while the fluid motor is rotating and the apparatus is in operation.

Instead of relieving the pressure by permitting the fluid under pressure to flow from the pipe 50 into the bottom of cylinder 16, the valve 51 may be closed and valve 55 opened whereby increases in pressure will tend to close the valve 54 and so decrease the pressure of the fluid supplied to the top of the cylinder 16 and thus decrease the force with which plunger 13 operates on the material 12. In case for any reason the reduction in force with which the plunger 13 presses upon the wood or other material 12 either by admitting the fluid under pressure to the bottom of the cylinder 16 or by the closing of the valve 54, does not give the required relief to the grinding or cutting tool 6, then the pressure in the passages 35 and 39 will simply be built up to a point at which the safety or relief valve 46 will operate and permit the excess fluid pumped therethrough

to escape through pipe 47 back to the supply tank 42. The relief valve may be adjusted to operate on various predetermined pressures.

Referring to Fig. 2, I there show a modified form of the grinding portion of the apparatus. As before, the grinding element 6 is rotated by the shaft 7, but instead of merely having one passageway 11 for the wood 12 or other material and one plunger 13 and piston 15 for operating the same, I have provided three similar feeds 57, 58 and 59, each adapted to contain a quantity of the material to be ground and feeding the same to the cutting tool at different points about the periphery of the same. Each of the feeds 57, 58 and 59 may be controlled by plungers operated by pistons in cylinders 60, 61 and 62 respectively, each being automatically controlled the same as the plunger, piston and cylinder shown in Fig. 1.

Referring to Fig. 4, I there show a modified arrangement for feeding the wood or other material into operative relation to the grinding or cutting wheel 6. This consists of a suitable container 63 preferably square or rectangular in cross-section and provided with a partition 64 dividing the space in the container into two passageways, said partition 64 stopping some distance short of the grinding member 6 whereby adjacent the grinding member the two passageways 65 and 66 merge into one at 67. Two plungers 68 and 69 are provided for operating in the passageways 65 and 66, respectively, these plungers being connected to pistons 70 and 71 operating in cylinders 72 and 73 respectively. When the wood in one passageway 65 is nearly used up, the plunger 68 may be raised without raising the plunger 69 and the passageway 65 refilled with wood or other material to be cut or ground and then the plunger 68 returned so that it will exert the desired pressure on the wood or other material to be ground in the passageway 65 and space 67. In the meantime the wood under the plunger 69 and in the space 67 has been suitably fed or pressed against the grinding wheel 6 by the plunger 69. Likewise, when the space or passageway 66 needs refilling, this may be done without discontinuing the grinding operation since the plunger 68 will properly feed the wood or other material in the passageway 65 and space 67 into operative engagement with the grinding element 6. With this arrangement the pressure with which each of the pistons 70 and 71 operate upon the material to be ground may be varied responsive to the variations in the load or resistance encountered by the grinding element as described in connection with Fig. 1.

Referring to Fig. 5 I have there shown an arrangement similar to that shown in Fig. 4 except that the two passageways 74 and 75 instead of being parallel to one another are

arranged at an angle to one another and in the passages 74 and 75 are suitable plungers 76 and 77 for forcing the wood or other material to be ground into engagement with the grinding member 6. In this case also either of the passages may be refilled while the material in the other passage is being ground or operated upon.

It will be understood that various parts in the drawings are not shown on the same scale and indeed the drawings are in many respects merely diagrammatic in order that the invention and improvements may be more clearly shown.

While I have described my improvements in detail and with respect to certain preferred forms, I do not desire to be limited to such details or forms, since many changes and modifications may be made and the invention embodied in widely different forms and kinds of apparatus for grinding or cutting many different kinds of materials in various ways.

It will be noted that in the preferred form of the invention described the pressure which is applied to the wood or other material to be ground tending to force it into engagement with the grinding element is varied in accordance with the amount of surface of wood exposed to the grinding element, the roughness of the grinding element and condition of the wood, etc., i. e., in accordance with the load or resistance offered by the material being ground and according to the invention in its preferred form the pressure on the wood is so varied and kept at such a value that the load on the apparatus will remain substantially constant and the grinding will proceed in the most efficient and rapid manner and so as to make the wood pulp or comminuted material of the proper and desired quality.

Since many changes and modifications may be made in the apparatus and the invention embodied in widely different forms and kinds of apparatus without departing from the spirit and scope of my improvements in their broader aspects, I desire to cover all modifications, forms and embodiments coming within the language or scope of any one or more of the appended claims.

What I claim as new and desire to secure by Letters Patent is:

1. Grinding apparatus having in combination a grinding member, a fluid pressure pump for operating said grinding member, means for holding the material being ground, means whereby operation of the grinding member builds up a fluid pressure varying with the load encountered by the grinding member, and means tending to decrease the pressure with which the material being ground is pressed against the grinding member responsive to increases in said fluid pressure.

2. Apparatus having in combination a

rotary cutting member, a driving shaft, means whereby operation of the driving shaft builds up a fluid pressure, means whereby said fluid pressure acts to rotate the cutting member, with a force proportional to said fluid pressure, means for holding the material to be cut in juxtaposition to the cutting member, and means regulating the pressure with which the material to be cut is forced against the cutting member responsive to variations in said fluid pressure.

3. The combination of a rotary cutting member, a driving shaft, means whereby operation of the driving shaft builds up a fluid pressure, means whereby said fluid pressure acts to rotate the cutting member, means for holding the material to be cut in juxtaposition to the cutting member, and means whereby the feed of the material being cut with respect to the cutting member is controlled responsive to variations in said fluid pressure.

4. The combination of a rotary cutting member, a driving shaft, means whereby operation of the driving shaft builds up a fluid pressure, means whereby said fluid pressure acts to rotate the cutting member, means for holding the material to be cut in juxtaposition to the cutting member and means independent of said driving shaft for limiting said fluid pressure.

5. The combination of a cutting member, means holding material to be cut in operative position with respect to the cutting member, a driving shaft, connections between the driving shaft and the cutting member whereby said shaft will operate the cutting member, said connections embodying means acting to build up a fluid pressure dependent upon the resistance encountered by the cutting member in its work, and means permitting the escape of the fluid under pressure when a predetermined pressure has been reached.

45 6. The combination of a cutting member, means holding material to be cut in operative position with respect to the cutting member, a driving shaft, connections between the driving shaft and the cutting member whereby said shaft will operate the cutting member, said connections embodying means acting to build up a predetermined fluid pressure dependent upon the resistance encountered by the cutting member in its work, and means whereby said predetermined pressure may be adjusted for different values.

7. The combination of a cutting member, means holding material to be cut in operative position with respect to the cutting member, a driving shaft, connections between the driving shaft and the cutting member whereby said shaft will operate the cutting member, said connections embodying means acting to build up a fluid pres-

sure dependent upon the resistance encountered by the cutting member in its work, and means whereby the pressure with which the material being cut engages the cutting member is controlled responsive to variations in said fluid pressure.

8. The combination of a cutting member, means holding material to be cut in operative position with respect to the cutting member, a driving shaft, connections between the driving shaft and the cutting member whereby said shaft will operate the cutting member, said connections embodying means acting to build up a fluid pressure dependent upon the resistances encountered by the cutting member in its work, means whereby the pressure with which the material being cut engages the cutting member is controlled responsive to variations in said fluid pressure, and means preventing the pressure of the fluid exceeding a predetermined value.

9. The combination of a rotary cutting member, means holding and pressing material to be cut into engagement with the cutting member, a driving shaft, a shaft driving the cutting member, means connecting said shafts and acting to build up a fluid pressure in accordance with the load encountered by the cutting member, and means whereby said fluid pressure acts to oppose the pressure forcing the material to be cut into engagement with the cutting member.

10. The combination of a rotary cutting member, means holding and pressing material to be cut into engagement with the cutting member, a driving shaft, a shaft driving the cutting member, means connecting said shafts and acting to build up a fluid pressure in accordance with the load encountered by the cutting member, and means whereby said fluid pressure acts to oppose the pressure forcing the material to be cut into engagement with the cutting member and means permitting the escape of said fluid under pressure when a predetermined pressure has been reached to limit the force actuating the cutting member.

11. Cutting apparatus having in combination a cutting member, a fluid pressure pump for operating said grinding member, means acting to build up a fluid pressure varying with the resistance encountered by the cutting member, means for holding the material to be cut and means acting to decrease the pressure with which the material being cut is pressed against the cutting member responsive to increases in said fluid pressure.

12. Cutting apparatus having in combination a cutting member, means acting to build up a fluid pressure varying with the resistance encountered by the cutting member, means for holding the material to be cut and means acting to decrease the pres-

sure with which the material being cut is pressed against the cutting member responsive to increases in said fluid pressure, said last mentioned means including a fluid pressure operated piston for forcing the material to be cut against the cutting member.

5 In testimony whereof I have signed my name to this specification.
